SKI HINGE

Filed Sept. 6, 1943

UNITED STATES PATENT OFFICE

2,367,528

SKI HINGE

Cecil B. Rollins, South Berwick, Maine

Application September 6, 1943, Serial No. 501,407

3 Claims. (Cl. 280—11.13)

My invention relates to folding skis of that class comprising a runner consisting of runner sections hingedly connected at abutting ends so that they may be relatively adjusted to occupy either extended end-to-end relationship while the ski is in use, or collapsed side-by-side relationship to reduce the length of the runner while the ski is not in use and while it is in storage or being transported.

The invention also has particular reference to the construction of the hinge or hinges by which the runner sections are connected.

The primary object of my invention is to provide an improved folding or collapsible ski of the class described but it is also an object of this invention to provide an improved hinge of simple, inexpensive and efficient construction which will be particularly adapted to be incorporated in a ski of the kind referred to.

To these ends I have provided an improved ski of the class described and also an improved hinge for incorporation therein, which in their preferred forms may be constructed and operate as set forth in the following description, the several novel features of the invention being separately pointed out and defined in the claims at the close of the description.

In the accompanying drawing:

Figure 1 is a side elevation of a folding ski constructed in accordance with this invention.

Figure 2 is a plan view of a portion of the folding ski shown in Fig. 1.

Figure 3 is a side elevation of the parts shown in Fig. 2.

Figure 4 is a section on line 4—4 of Fig. 2.

Figure 5 is a section on line 5—5 of Fig. 2.

Figure 6 is a section on line 6—6 of Fig. 2.

Figures 7 and 8 are details of one of the locking bolts hereinafter described.

Figure 9 is an elevation of the pintle hereinafter described.

The runner of the ski shown in Fig. 1 of the drawing comprises three sections including a front section 10, an intermediate section 11 and a rear end section 12, these three sections being shown in full lines as occupying their extended relationship. The rear end of front section 10 abuts the forward end of the intermediate section 11 to which it is pivotally connected by means of a hinge 13 constructed in accordance with my invention, while the forward end of the rear section 12 abuts the rear end of said intermediate section to which it is also pivotally connected by means of another hinge 13a of similar construction.

Since the hinges 13 and 13a are alike in construction a description of one will suffice for both, but it may be pointed out here that these two hinges permit of adjustment of the end sections 5 so that they may be caused to occupy either the extended positions shown by full lines (Fig. 1) or the infolded positions indicated by broken lines, each hinge being so constructed as automatically to lock its end section in each position when said section is unlocked and moved from one position to the other.

The hinge 13 comprises three apertured lugs or arms 14, 15 and 16 which constitute rigid extensions of the front runner section 10 since they 15 are integral parts of a plate 17 fixed in position upon the top side of said section, adjacent to the rear end of the latter, by means of bolts 18. The lug or arm 15 is disposed midway between the two lugs or arms 14 and 16 and the apertures 20 of said three lugs are aligned transversely with respect to the runner and also disposed directly above or opposite the joint between the abutting ends of runner sections 10 and 11 when the runner is in its extended condition.

25 The three lugs 14, 15 and 16 are disposed between two apertured lugs or arms 17 and 18 which constitute rigid extensions of the intermediate runner section 11 since they are integral with plates 19 and 20, respectively, which are rigidly 30 fastened by bolts 21 to said intermediate section.

The aperture 22 of the middle lug 15 (Figs. 2 and 6) is made square in cross-section to receive within it and fit the squared middle portion 23 (Fig. 9) of a pintle 24 so that said lug 15 and 35 pintle 24 cannot rotate relatively to each other but must turn as one unit. The lugs 17 and 18 fit against the outer faces of lugs 14 and 16, respectively, so that the two runner sections are held against sidewise displacement relatively to 40 each other.

The apertures 25 of lugs 14 and 16 (Figs. 2 and 5) are cylindrical and each has loosely fitted within it an exteriorly cylindrical bolt sleeve 26 whose interior is made square as viewed in cross-45 section to loosely fit upon the squared intermediate portion 23 of pintle 24, the opposite ends of said square intermediate portion abutting the lugs 17 and 18 at its corners.

Thus the two clutch sleeves are, in effect, 50 splined on the pintle so that while said sleeves must rotate with the pintle and runner section 10 they may be adjusted axially on pintle 24 toward and from the outer lugs 17 and 18.

The squared portion 23 of pintle 24 is provided 55 at its opposite ends with trunnions 27 which are

rotatably supported within cylindrical apertures 28 (Figs. 2 and 4) formed in the lugs 17 and 18.

The outer end of each bolt sleeve 26 is made with two segmental bosses 29 (Figs. 2, 4 and 5) disposed at opposite sides of the axis of said sleeve, said bosses being adapted to occupy two segmental sockets 30 provided upon the inner side or face of the proximate lug or arm 17 or 18. While I have herein shown two bosses 29 on each bolt sleeve 26 it is to be understood that a single boss would serve my purpose but would not withstand the shocks and stresses to which the hinge is subjected while the ski is in use, as well as two bosses.

Mounted on pintle 24 between each bolt sleeve 26 and the middle lug or arm 15 is provided a coiled spring 31 which yieldingly holds its sleeve in engagement with its lug or arm 17, or 18.

It will be clear that when the runner is in extended condition as shown by full lines in the drawing, the bosses 29 occupy the sockets 30 and serve to positively lock the runner sections against relative pivotal displacement. It will also be clear that by manually retracting bolt sleeves 26 the end runner sections may be unlocked and swung on the hinge 180 degrees into positions alongside intermediate section 11 as indicated by broken lines in Figs. 1 and 3, whereupon the spring pressed clutch sleeves 26 again interlock with the lugs or arms 17 and 18 and positively lock the sections of the runner in their collapsed or folded condition.

As shown in Fig. 2 the bosses 29 taper toward their free ends while the side walls of the sockets 30 are of complementary shape so that the sides of the bosses 29 seat against said side walls before the ends of the bosses engage the bottoms of the sockets. In this way the bosses always fit snugly into the sockets thereby preventing any play between the runner sections.

The inner ends of the bolt sleeves are preferably made with radial flanges for use in retracting said sleeves when the runner sections are to be adjusted relatively.

What I claim is:

1. A folding ski comprising two runner-sections having their front and rear ends, respectively, disposed in proximity to each other and made with intermeshing apertured lugs; a pintle occupying said apertures and pivotally connecting

said lugs so as to provide for angular adjustment of said sections relatively, said pintle being non-rotatably connected with one of the lugs of one of said sections; two bolt sleeves slidably splined on said pintle with one of said sleeves slidably mounted within the aperture of one of the lugs of said last-mentioned section and the other sleeve slidably mounted within the aperture of another lug of said last-mentioned section, said bolt sleeves being engageable with lugs of the other section to rigidly lock said sections against angular displacement relatively, and means for holding said sleeves in locking engagement with said last-mentioned lugs while said sections are at the limit of their angular adjustment relatively in each direction, said sleeves being manually operable to disengage the same from said last-mentioned lugs.

2. A folding ski constructed in accordance with claim 1 and wherein said last-mentioned holding means consists of two springs, one for each bolt sleeve.

3. A structure comprising two sections having straight marginal portions disposed in proximity to each other, and a hinge pivotally connecting said sections comprising intermeshing apertured lugs fastened to said sections; a pintle occupying said apertures and pivotally connecting said lugs so as to provide for angular adjustment of said sections relatively, said pintle being non-rotatably connected with one of the lugs of one of said sections, two bolt sleeves slidably splined on said pintle with one of said sleeves slidably mounted within the aperture of one of the lugs of said last-mentioned section and the other sleeve slidably mounted within the aperture of another lug of said last-mentioned section, said bolt sleeves being engageable with lugs of the other section to rigidly and positively lock said sections against angular displacement relatively, and spring means holding said sleeves in locking engagement with said last-mentioned lugs while said sections are at the limit of their angular adjustment relatively in each direction, said sleeves being manually retractile to disengage the same from said last-mentioned lugs when said sections are to be angularly adjusted relatively.

CECIL B. ROLLINS.
